FOREIGN PATENT DOCUMENTS

GB 3000756 * 12/2002

Primary Examiner—Ian Simmons*Assistant Examiner*—Dana Sipos(74) *Attorney, Agent, or Firm*—Nixon & Vanderhye(57) **CLAIM**

The ornamental design of a squeeze bottle, as shown and described herein.

DESCRIPTION

FIG. 1 is a perspective view from the bottom and left hand side of a bottle according to a first embodiment of the design, including a cap portion;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view thereof from the bottom and left side showing the cap in an open position;

FIG. 9 is a perspective view from the bottom and left side of a bottle according to a second embodiment of the design, including a cap portion;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof; and,

FIG. 16 is a perspective view thereof from the bottom and left side showing the cap in an open position.

The broken lines shown in the drawings are for illustrative purposes only and form no part of the claimed design.
